UNITED STATES PATENT OFFICE.

CHARLES H. MILLER AND KNUT A. READ, OF OSKALOOSA, IOWA.

HYDRANT.

1,218,950.

Specification of Letters Patent. Patented Mar. 13, 1917.

Application filed April 25, 1916. Serial No. 93,434.

To all whom it may concern:

Be it known that we, CHARLES H. MILLER, a citizen of the United States, and KNUT A. READ, a subject of the King of Sweden, residing at Oskaloosa, in the county of Muscatine and State of Iowa, have invented certain new and useful Improvements in Hydrants, of which the following is a specification.

10 This invention relates to hydrants and has special reference to means for controlling the flow of water through the hydrant as it is needed. One object of the invention is to provide a hydrant of such construction that 15 a copious flow will be permitted so that the device may be advantageously employed as a fire plug. Another object of the invention is to provide efficient means for draining the device of water which might accumulate 20 therein after the flow has been cut off so that damage to the hydrant due to freezing of such accumulated water will be prevented. A still further object of the invention is to provide means whereby when the cut-off 25 valve is opened, the drain valve will be automatically closed without any particular attention upon the part of the operator.

Other incidental objects of the invention will appear as the description of the same 30 proceeds and the invention resides in certain novel features which are illustrated in the accompanying drawings and will be more particularly pointed out in the claims following the detailed description.

35 In the annexed drawings:

Figure 1 is a vertical section of the lower portion of a hydrant embodying our improvements;

Fig. 2 is a horizontal section on the line 40 2-2 of Fig. 1;

Fig. 3 is a transverse vertical section on the line 3-3 of Fig. 1;

Fig. 4 is a detail horizontal section on the line 4-4 of Fig. 1;

45 Fig. 5 is a detail perspective view of a portion of the casing.

In carrying out our invention we employ a boot-like casing 1 which is adapted at its upper end to be secured to a conduit or hydrant body 2 which will be secured in the ground in any well known manner and is constructed at its upper end (not shown) with the usual outlets. The boot-like casing 1 constitutes the lower end of the hydrant 50 and is provided with a lateral offset 3 which

is to be secured to the water main, as will be readily understood. The lower wall of the offset 3 extends into the vertical plane of the main body of the casing 1, as shown at 4, and at the inner end of the offset 3 is a valve 50 seat 5 which may be merely a beveled face formed around the opening which establishes communication with the water main or may be a removable ring or lining, as illustrated. Depending from the bottom 4 of the casing 55 is a drain spout 6 through which any water which might collect within the casing, after the port defined by the valve seat 5 is closed, may escape.

The casing 1 gradually reduces in diameter toward its upper end, as clearly shown in Fig. 1, and one inner wall of the said casing is vertical, as shown at 7. The said vertical wall 7 is disposed in alinement with one wall of the body 2 and upon the sides of 70 the casing 1, parallel with the said wall 7, are ribs 8 which project toward each other and constitute guides which are engaged by the gear casing 9 to thereby prevent rotation of said casing. Smaller offsets 10 are 75 also provided upon the inner surface of the casing between the ribs 8 and the adjacent wall 7 so that grooves 11 will be formed to receive the offsets or lugs 12 upon the gear casing to further aid in holding the casing 80 in its proper position within the main casing 1. The grooves 11 also receive the ends of 85 the guiding arms 13 upon the drain valve, as will be presently more fully set forth. The gear casing 9 is constructed in two members 90 disposed one above the other and firmly secured together by bolts 14 inserted vertically therethrough, as will be readily understood. The gear case 9 contains three beveled gears which intermesh and serve to operate the cut 95 off valve and the drain valve. The driving gear 15 is formed on or secured to the lower end of a spindle 16 which is journaled in the upper end of the gear case 9 and has an angular upper extremity 17. A coupling 100 sleeve 18 is secured to this angular extremity 17 of the spindle and is also secured to the lower end of an angular turning rod 19 which extends up to the upper end of the body 2 and is there supported in any convenient manner so that the weight of the gear case 9 and the parts mounted in or carried thereby will be sustained by the said operating rod. Inasmuch as the mechanism at the upper end of the hydrant may be of any 105 110

well known form and forms no part of our present invention, it is not illustrated in the accompanying drawings but it is thought the manner of manipulating the same will 5 be readily understood by those skilled in the art. The driving gear 15 is a beveled pinion, as shown clearly in Fig. 1, and meshes with an intermediate beveled gear 20 which has an elongated hub journaled at its opposite ends in the opposite sides of the gear case 9, as shown at 21 and 22. This hub is 10 internally threaded, as shown at 23, and receives the threaded spindle 24 of the cut-off valve. The gear 20 is driven by the pinion 15, as is obvious, and also meshes with a beveled pinion 25 which has a hub or spindle 26 journaled in the lower end of the gear case 9 and provided with a threaded extremity 27 depending therefrom to operate the drain 15 valve, as will presently particularly appear. The cut off valve comprises a disk or plate 28 which has a central offset portion whereby to form a socket 29 in its inner face which is adapted to fit over the inner projecting 20 end of the hub of the gear 20 so that the cut off valve may be withdrawn from its seat to the greatest possible extent and thereby permit an uninterrupted inflow of the water. The disk or plate 28 is fitted upon a 25 smooth cylindrical portion 30 at the end of the valve spindle and the extremity of this portion 30 is threaded, as shown at 31. A rubber or fabric washer 32 is fitted upon the portion 30 of the valve spindle against the 30 plate or disk 28 and a metallic washer 33 is placed upon the spindle against the said fabric washer, a nut 34 being engaged upon the threaded terminal 31 and turned home against the metallic washer so as to clamp 35 the washer 32 firmly into place. It will be readily understood that the washer 32 will be more or less elastic and fits against the valve seat 5 so that, when the valve is moved outwardly to its full extent, the inflow of 40 water will be effectually cut off. The disk or plate 28 is provided upon its edge at diametrically opposite points with lateral lugs or projections 35 which engage under the short ribs 36 formed on the inner opposite 45 walls of the casing 1 so that rotation of the valve will be prevented and it will be forced to move in a rectilinear path. At the lowest point of its edge, the plate 28 is provided with an additional lug or projection 37 50 which is adapted to ride upon a rib 38 formed longitudinally of the bottom extension 4 of the casing to further prevent rotation of the valve. The floor of the extension 4 of the casing is inclined at opposite sides 55 of the rib 38, as shown at 39, in Fig. 3, and by dotted lines in Fig. 1, so that any water which might tend to collect in the casing will be directed to the drain spout 6. In order to permit the fullest possible flow of 60 water when it is needed and to free the cas- 65

ing as fully as possible of all projections which might tend to retard or restrict the inflow, the ribs 36 do not extend the full length of the casing but are very short and the valve disk or plate is formed with wings 70 40 at opposite sides of its spindle which are adapted to fit against the opposite sides of the gear case 9 and thereby prevent rotation of the valve during the interval when the lugs 35 will be out of engagement with the 75 said ribs 36.

The drain valve comprises a sleeve or ring 41 which is internally threaded to engage and be supported by the threaded spindle 27 and this ring, collar, or sleeve is mounted within a thimble 42 which is threaded into a shoulder or partition 43 formed on the inner surface of the drain spout as clearly shown in Fig. 1. The sleeve 41 is of less diameter than the internal diameter of the thimble 42 so that a space for the passage of water will be provided between the thimble and the sleeve. The guide arms 13 are formed integral with the upper end of the sleeve 41 and the lower end of the sleeve is provided with a pin 44 upon which is fitted an elastic washer or valve body 45 which is secured in place by a nut 46 mounted upon the pin 44 and turned home thereon against a washer 47 which bears against the elastic washer or disk 45. Outlet ports 48 are provided in the thimble 42 below the partition 43 and it will be obvious that, when the drain valve is at the lower limit of its movement, as shown in Fig. 1, any 100 water which may be within the casing above the partition 43, will flow to and through the said ports. The spout 6 may be connected in any convenient or preferred manner with the water main so that this water 105 will be returned to the main or, if it be desired to guard against the water from the main backing up in the hydrant, the drain may be connected with a sewer or any other outlet.

It is thought the use and advantages of our improved device will be readily understood and appreciated from the foregoing description taken in connection with the accompanying drawings. When the hydrant is not in use, the parts will be arranged as shown in Fig. 1, the cut off valve being seated and the drain valve being lowered so as to open the drain ports. When it is desired to draw water, the operating rod 19 is rotated by means of a spanner or other tool applied to its upper end and the rotation of this rod will be imparted directly to the beveled pinion 15 which will direct the actuating gear 20 and through the same 115 transmit rotation to the gear 25. The rotation of the gear 20 will, through the engagement of the hub with the threaded spindle 27, withdraw the cut off valve from its seat so that the inlet port will be uncov- 120 125 130 135 140

ered or opened and, consequently, the water will flow from the main into the casing 1. As the cut off valve recedes from its seat, the drain valve will be raised so that the 5 disk or washer 45 will be brought over and above the drain ports 44 and, consequently, the water cannot escape through the said ports but will be held within the casing. When the cut off valve is fully withdrawn, 10 a large clear passage for the water will be established and the water will flow rapidly and in a large volume into the body 2 and rise through the same to the outlet pipes. It will, of course, be understood that the 15 threaded spindles 24 and 27 will be so relatively proportioned that the drain valve will have a more limited movement than the cut off valve so that, while the cut off valve will move rapidly and over a relatively long 20 path, the drain valve will move very slowly and over a relatively short path so that while the drain valve will have sufficient movement to cut off the flow through the drain ports, its movement will not be so extensive as to require the provision of a long 25 drain spout or entail unnecessary weight and bulk in the lower portion of the casing. The guide arms 13 not only cause the drain valve to move steadily when it is being 30 opened or closed but also serve to prevent rotation of the said valve and, consequently, compel it to move in a rectilinear path.

Our device is exceedingly simple in the construction and arrangement of its parts 35 and by the peculiar formation of the casing ample accommodation for the gearing is provided. The gearing will be positively operated so that the valves will be moved easily to be opened or closed. The engagement 40 of the parts and the form of the casing facilitates the assembling of the mechanism so that the casing 1 which forms the lower end of the hydrant may be set in position and connected with the water main 45 either before or after the valves and the operating gearing are placed within the same. When the cut off valve is fully withdrawn it will lie entirely within the area defined by the upper end of the casing and 50 will be between the ends of the ribs or the shoulders 36 and the gear case 9. If, therefore, the cut off valve be assembled with the other parts in the same relative position it will occupy when the flow of water is permitted, the entire assembled mechanism may 55 be inserted through the upper end of the casing and moved downwardly to the operative position, the ends of the guide arms 13 and the projections 12 engaging the groove 60 11 and thereby guiding the parts in their downward movement. The gear case 9 is provided with grooves or notches which engage the rib 8, as shown clearly in Fig. 2, so that the proper positioning of the valves 65 and the gearing within the casing will be

positively insured. Of course, if any repairs should become necessary, the parts may be removed in the reverse manner. After the casing has been placed in position and the gear case 9 with the valves has been 70 lowered into the casing, the operating rod 9 is inserted so that its lower end will engage the coupling 18 which is then fastened to the rod in any preferred manner. The described operation of assembling the parts 75 will be readily understood upon reference to the dotted lines in Figs. 1 and 2 which indicate the open position of the cut-off valve.

Having thus described our invention, what 80 is claimed as new is:

1. In a hydrant, the combination of a casing having an inlet port in its side and provided with laterally extending guides adjacent the port, a valve to open or close said port and constructed to engage said guides, and means for moving the said valve laterally to or from the inlet port, the range of movement of the valve exceeding the extent of the said guides whereby when the valve 90 is fully opened, it may be moved across the ends of the guides and withdrawn from the casing with the operating mechanism.

2. In a hydrant, the combination of a casing having a lateral offset forming an inlet 95 and having a drain spout depending from its lower end, the floor of the said casing at one side of said drain spout being inclined from the inlet to said spout, a valve movable over said floor to and from the inlet, a 100 valve controlling the flow through the drain spout, and means for simultaneously operating said valves.

3. In a hydrant, the combination of a casing having vertically disposed guides on its 105 inner wall and having an inlet spaced laterally from the said guides, a gear case fitted within the casing and engaging said guides, a valve to control the flow through said inlet, gearing journaled in and housed within 110 the gear case, operative connection between said gearing and valve, and means for actuating said gearing.

4. In a hydrant, the combination of a casing, a gear case mounted therein, a gear 115 disposed transversely in the said gear case and having a hollow internally threaded hub, means for actuating said gear, a valve controlling the flow into the casing, and a threaded spindle for said valve engaging the 120 internally threaded hub of the said gear.

5. In a hydrant, the combination of a casing having an inlet in one side and having guides on its opposed walls adjacent the said inlet, a gear case mounted within the 125 said casing, a valve arranged to control the flow through the inlet and constructed to engage the guides adjacent the inlet, wings projecting from the valve to bear against the opposite sides of the gear case, gearing with- 130

in the gear case operatively connected with said valve, and means for actuating said gearing.

6. In a hydrant, the combination of a casing having an inlet port in one side and provided on opposed walls with vertically disposed guides, a gear case mounted within the casing, a thimble secured in the lower end of the casing and having ports formed there-
10 in, a valve arranged to control the flow through the inlet, gearing within the gear case operatively connected with the said valve and including a member having a

threaded spindle depending from the gear case, a sleeve fitted upon the said threaded spindle and disposed within the said thimble and spaced annularly therefrom, guide arms fixed to the upper end of said sleeve and engaging the guides on the casing, and a valve carried by the lower end of said sleeve and arranged to cover or uncover the ports in the thimble.

In testimony whereof we affix our signatures.

CHARLES H. MILLER. [L. S.]
KNUT A. READ. [L. S.]
